UNITED STATES PATENT OFFICE.

THOMAS ELMER SOWERS AND BYRD L. HARLACHER, OF HARRISBURG, PENNSYLVANIA.

TOY.

Application filed July 7, 1923. Serial No. 650,047.

To all whom it may concern:

Be it known that we, THOMAS ELMER SOWERS and BYRD L. HARLACHER, citizens of the United States, residing at Harrisburg, in the county of Dauphin and State of Pennsylvania, have invented new and useful Improvements in Toys, of which the following is a specification.

This invention relates to amusement devices, particularly to toys, and has for its object the provision of a novel toy designed to be driven by wind power or by hot air ascending from a radiator or discharged from a register, the toy simulating a man sawing wood, the saw being driven by rotation of the wind or heat wheel.

An important object is the provision of a figure toy of this character which will require no attention but which will be continuous and automatic in operation as long as the operating wheel is rotated by wind power or currents of hot air.

Another object is the provision of a toy of this type in which a heat wheel and wind wheel may be used interchangeably, a peculiar mounting being provided for installing the wind wheel.

An additional object is the provision of a toy which will be simple and inexpensive in manufacture, pleasing and amusing in action, durable in service and a general improvement in the art.

With the above and other objects and advantages in view the invention consists in the details of construction to be hereinafter more fully described and claimed and illustrated in the accompanying drawings, in which:

Figure 1 is a side elevation of the device,
40 Figure 2 is a front view,

Figure 3 is a detail section through the upper end of the operating shaft showing the mounting of the heat wheel thereon,

Figure 4 is a detail plan view of the heat
45 wheel,

Figure 5 is a front elevation showing the heat wheel removed and replaced by the wind wheel structure,

Figure 6 is a detail section on the line
50 6-6 of Figure 5 showing means for holding the driving gear permanently associated with the supporting bracket.

Referring more particularly to the drawings we have shown our device as comprising a suitable supporting base 10 upon one

end of which is mounted a miniature saw horse 11 which carries a length or billet 12 of wood formed with a saw kerf 13.

Suitably mounted upon the base in somewhat spaced relation to the saw horse is a figure 14 representing a man leaning forward slightly in a position which would be natural to a person sawing wood. On one side of this figure is an arm 15 which has its hand portion resting upon the billet of wood in a realistic manner and pivoted at 16 on the body is a movable member 17 which includes a head 18 and an arm 19.

The numeral 20 designates a saw which is movable within the kerf 13 and which has one end pivoted at 21 on the hand portion of the arm 19 and which has its other end pivotally connected with a crank arm 22 at one end of a rock shaft 23 which is journaled in suitable bearings 24 on the base and which has its other end formed with an upstanding crank arm 25.

Rising from the base at some convenient point is a standard 26 secured in any desired manner at its lower end and having its upper end formed with a lateral extension 27 terminating in an eye 28 which forms a bearing for a vertical shaft 29 which has its lower end journaled in a step bearing 30 mounted on the base. Intermediate its ends this shaft is formed with a crank 31 on which is engaged a pitman 32 which is in turn pivotally connected with the crank arm 25. The shaft 29 extends above the extension 27 and has its upper extremity formed angular in cross section as indicated at 33.

In some of the figures of the drawing we have shown the shaft 29 as provided at its upper end with what we call a heat wheel 34 which is simply a disk of sheet metal, card board or other sheet material cut radially to provide a plurality of vanes 35 which are curved laterally as shown. This wheel is mounted upon the shaft between two washers 36 of leather or the like which are slipped onto the angular portion 33 of the shaft.

In the operation the device is placed either on a radiator or at such a point that the draft from a heat register may impinge upon the underside of the wheel. This air current will cause pressure against the underside of the wheel and this pressure acting on the vanes will cause rotation of the wheel. As the shaft is turned the pitman 32 con-

nected with the crank arm 25 rocks the shaft 23 and the arm 22 thereon moves the saw back and forth in a very realistic manner, the pivoted arm and head of the figure 5 swinging in accordance with the movement of the saw.

Instead of using a heat wheel, we may use a wind wheel as shown in certain other figures of the drawing, which wind wheel structure is capable of being mounted upon the shaft 29 to replace the wheel 34. In carrying out this feature of the invention we provide a U-shaped frame 37 having a bearing portion 38 slipped over and rotatable with 10 respect to the upper end of the shaft 29, this bearing portion resting upon the extension 27. Either formed as a continuation of or secured upon the frame 27 is a tail frame 39 which may be formed with the member 15 27, both being constructed together from a single length of wire. This tail frame 39 would be covered by a piece of sheet metal 40 having its edges rolled over the edges of the frame 39 though of course some 20 other but equivalent structure may be used if preferred. Journalized in the frame 37 is a shaft 41 upon one end of which is secured the wheel 34. The intermediate portion of this shaft carries a beveled gear 42 which 25 meshes with a beveled gear 43 having a socket of a size and shape to be engaged upon the angular end 33 of the shaft 29. It is preferable that the gear 43 be held permanently associated with the frame 37 and in 30 mesh with the gear 42 and to accomplish this we may provide a transverse brace 44 extending across the frame 37 and having a bearing portion 45 engaged within a peripheral groove 46 in the hub of the gear 43.

40 The operation of this second form is of course the same as that of the first described form except that the device is placed at an open window or at any location where a draft of air may impinge upon the wheel. 45 It is to be noted that the same wheel is used in either instance, as it is so constructed as to fit upon either the shaft 29 or the shaft 41 and the device might be made and sold in either form so that the wind wheel attachment might be removed and the wheel placed directly on the shaft 29 for operation in connection with a radiator or register. 50 While we have shown and described the preferred embodiment of the invention it is of course to be understood that we reserve the right to make such changes in the form, construction and arrangement of parts as will not depart from the spirit of the invention or the scope of the subjoined claims.

Having thus described our invention we claim:

1. In a toy of the character described, a reciprocatory element, an upstanding U-shaped member having its bight portion

70 journally supported and having one arm connected with said reciprocatory element, an upstanding supporting bracket having a horizontal extension at its upper end, a vertical shaft journaled through said extension and formed with a crank portion, a pitman pivotally connected with the other arm of said U-shaped member and with said crank portion, a wind wheel having means for engagement upon the upper end of said shaft, whereby to drive the same directly, and a selectively usable indirect drive for the shaft comprising a frame adapted to be mounted upon said extension and carrying a countershaft having means for engagement of said wheel thereon, a gear on said counter shaft and a gear within the frame meshing with said first named gear and formed for connection upon the upper end of said vertical shaft. 75

2. In a toy of the character described, a reciprocatory element, an upstanding U-shaped member having its bight portion journally supported and having one arm connected with said reciprocatory element, an upstanding supporting bracket having a horizontal extension at its upper end, a vertical shaft journaled through said extension and formed with a crank portion, a pitman pivotally connected with the other arm of said U-shaped member and with said crank portion, a wind wheel having means for engagement upon the upper end of said shaft, whereby to drive the same directly, and a selectively usable indirect drive for the shaft comprising a frame adapted to be mounted upon said extension and carrying a countershaft having means for engagement of said wheel thereon, a gear on said countershaft and a gear within the frame meshing with said first named gear and formed for connection upon the upper end of said vertical shaft. 80

3. A toy of the character described comprising a base, a miniature saw horse mounted thereon and supporting a billet of wood having a kerf therein, a figure mounted on the base adjacent the saw horse and having a movable arm and head portion, a saw pivotally connected with the extremity of said arm movable within said kerf, a rock shaft journaled on the base and having one end carrying an upstanding crank arm connected with the free end of said saw, means for rocking said shaft, comprising a vertical support formed with a bearing extension, a vertical shaft journaled through said bearing extension and projecting there above, said shaft being formed with a crank portion, a second crank arm on said rock

shaft, a pitman connecting the second named crank arm with the crank portion of said shaft, a wind wheel for rotating said vertical shaft and having a socket, a counter-
5 shaft carrying a beveled gear, a frame journally receiving the counter-shaft and rotatably engaged upon the extension, a guide tail on said frame, a beveled gear rotatable in the frame in mesh with said first named
10 gear and having a socket for engagement upon the upper end of the vertical shaft, said

wheel being interchangeably usable with its socket engaged upon said counter-shaft or upon the upper end of the vertical shaft subsequent to removal of the wheel from said counter-shaft and removal of the frame from the vertical shaft. ¹⁵

In testimony whereof we affix our signatures.
